(57) **ABSTRACT**

A new *Osteospermum* plant particularly distinguished by about 27 inflorescences per plant and with an upright habit and good branching, is disclosed.

1 Drawing Sheet

1

Genus and species: *Osteospermum ecklonis* Norl.
Variety denomination: 'KLEOE24785'.

BACKGROUND OF THE NEW PLANT

The present invention comprises a new and distinct variety of *Osteospermum*, botanically known as *Osteospermum ecklonis* Norl., and hereinafter referred to by the variety name 'KLEOE24785'. 'KLEOE24785' originated from a cross-pollination conducted in summer 2019 in Stuttgart, Germany between the proprietary female *Osteospermum* variety 'OE-2015-2410' (unpatented) and the proprietary male *Osteospermum* variety 'KLEOE21535' (unpatented).

The seeds from the cross were collected and sown in January 2020 in Latina, Italy and the plants were grown for evaluation. An individual plant designated 'KLEOE24785' was selected in May 2020 in Latina, Italy. In May 2020 'KLEOE24785' was first vegetatively propagated by vegetative terminal cuttings in Latina, Italy. 'KLEOE24785' was found to reproduce true to type in successive generations of asexual propagation via vegetative cuttings.

SUMMARY

The following are the most outstanding and distinguishing characteristics of this new variety when grown under normal horticultural practices in Stuttgart, Germany.

1. About 27 inflorescences per plant;
2. Upright habit; and
3. Good branching.

DESCRIPTION OF THE PHOTOGRAPH

This new *Osteospermum* plant is illustrated by the accompanying photograph which shows a close-up of the foliage, buds, and mature inflorescences. The photograph is of an 11-week-old plant grown indoors in Stuttgart, Germany in

April 2023. The colors shown are as true as can be reasonably obtained by conventional photographic procedures.

DESCRIPTION OF THE NEW VARIETY

The following detailed descriptions set forth the distinctive characteristics of 'KLEOE24785'. The data which define these characteristics were collected in Stuttgart Germany on May 14, 2025 on plants potted in Mar. 3, 2025. References are to The R.H.S. Colour Chart of The Royal Horticultural Society of London (R.H.S.), 5th edition (2007). Classification:

Family.—Asteraceae.

Botanical.—*Osteospermum ecklonis* Norl.

Common.—*Osteospermum*.

Designation.—'KLEOE24785'.

Parentage:

Female parent.—'OE-2015-2410' (unpatented).

Male parent.—'KLEOE21535' (unpatented).

Plant:

Form and habit.—Herbaceous perennial but usually cultivated as an annual; not frost resistant.

Growth habit.—Upright.

Branching habit.—Normal.

Height (from top of soil, including inflorescence).—15.0 cm.

Width (including inflorescences).—26.0 cm.

Propagation.—Vegetative cuttings.

Time to produce a finished flowering plant.—10 to 17 weeks.

Time to initiate and develop roots.—4 weeks.

Root description.—Fine; RHS 155A (white).

Leaves:

Arrangement.—Alternate.

Shape.—Obovate.

Apex.—Acute.

Base.—Acute.

Margin.—Entire.
